UNITED STATES PATENT OFFICE.

HERMAN A. POPPENHUSEN, OF CHICAGO, ILLINOIS.

SPRING.

1,135,319.

Specification of Letters Patent. Patented Apr. 13, 1915.

Application filed April 8, 1914. Serial No. 830,554.

To all whom it may concern:

Be it known that I, HERMAN A. POPPENHUSEN, a citizen of the United States, and a resident of Chicago, in the county of Cook and State of Illinois, have invented certain new and useful Improvements in Springs; and I do hereby declare that the following is a full, clear, and exact description thereof, reference being had to the accompanying drawings, and to the letters of reference marked thereon, which form a part of this specification.

This invention relates to improvements in vehicle springs and more particularly to that class of springs comprising in their construction a series of superimposed flexible plates or bars, said series of plates being secured together at their central portions, and adapted to move lengthwise relative to each other, as the weight supported by the spring is increased and decreased.

The principal object of this invention is to provide a construction for vehicle springs embodying a simple and effective means for reducing the friction between the plates.

My invention therefore consists in the matters hereinafter described, more particularly pointed out in the appended claims and illustrated in the accompanying drawings, in which—

Figure 1 is a view in elevation of a spring provided with my improved means for reducing friction between the leaves; Fig. 2 is an enlarged fragmentary view in section of two superimposed spring leaves with one form of friction roller mounted between them; Fig. 3 is an enlarged plan view, showing one form of roller mounted between two leaves; Fig. 4 is an enlarged fragmentary view similar to Fig. 2, showing a modified construction; Fig. 5 is an enlarged plan view, showing a modified form of roller; Fig. 6 is a perspective view of one form of roller, such as shown in Figs. 2 and 3; and Fig. 7 is a perspective view of a modified form of roller, such as shown in Figs. 4 and 5.

Referring to the drawings, a spring embodying the features of my invention comprises a plurality of superimposed plates or leaves 10, said leaves consisting of elongated plates or strips of flexible sheet metal of unequal lengths (Fig. 1), the uppermost leaf being the longest and the length of each succeeding leaf being proportionally decreased, so that the end portions of each

leaf projects substantially the same distance beyond the leaf immediately below. The leaves are connected together at their central portions by means of straps 11, 11, 60 surrounding the same, although other means such as a bolt extending through the leaves may be employed. The spring leaves are provided with a suitable degree of curvature, as is the practice in constructing 65 springs of this form, so that the upper surfaces thereof are concave.

The upper spring leaf is provided at its ends with eye bolts 12, by means of which the vehicle or other body is attached, the 70 spring being supported at its midpoint upon the axle or the like by suitable securing means, herein shown as the eye bolt 13, attached to the under side of the spring by means of the straps 11, 11. 75

The spring is arranged to be acted upon by a plurality of parallel forces, to wit, a downward force at each end of the spring, and an upward force at the center thereof, and intermediate of the ends. As these 80 opposed forces are increased and decreased the spring tends to be flexed from its position of normal curvature to a straightened position, and vice versa, with the attendant lengthwise movement of the leaves relative to each 85 other, this movement being ordinarily in the nature of a sliding of one plate upon the other. The extent of the movement is obviously greatest at the extreme ends of the spring leaves, and for that reason the maximum degree of friction is produced 90 throughout said end portions.

In order to eliminate so far as possible the friction between the spring leaves and the undesirable effects thereof, I propose to 95 provide the following arrangement of anti-friction devices in the form of rollers 14 adapted to be mounted between the end portions of the leaves, as shown in Fig. 1.

Referring now to the construction of one 100 of these devices and the manner of mounting the same, the construction of a preferable form may be understood from the following: A roller 14, comprising a cylindric body of hard metal having a length substantially 105 equal to the width of the spring leaves, is adapted to be inserted transversely between the end portions of the leaves 10, 10, and to be revolved in either direction by the relative movement of the spring leaves in contact with the roller. At each end of the 110 roller are provided semi-circular shaped

flanges 15, 15, said flanges being located in corresponding positions upon the ends of the roller. As a preferable construction, the flanges are formed integral with the rollers 5 although they may be equally well attached in any suitable manner. The flanges are of a thickness sufficient to prevent their being easily broken, and of a radius slightly greater than the thickness of the plates 10, 10 so that the lower portions of the flange are adapted to extend beyond the lower surface of the spring leaf immediately below the roller. The upper surfaces 16 of the extremities of the flanges are preferably inclined toward the axis of the roller for the purpose hereinafter set forth.

Within the longitudinal margins of the spring leaf and adjacent to the end thereof are formed two recesses 17, 17, preferably 20 rectangular in form. These recesses are arranged in opposite relation and act as guides for the rollers, in that they are adapted to receive the flanges 15, 15 of the roller. The width of the recesses is substantially equal 25 to the thickness of the flanges, the length of the recesses being somewhat greater than the diameter of the flanges, thereby affording sufficient space for the longitudinal movement of the roller as the same is rotated 30 by the lengthwise movement of the leaves relative to each other. By means of the combination of the flanges and recesses the rollers are retained in position, being permitted to roll lengthwise through a limited 35 distance, but are prevented from further movement by the contact of the flanges 15, 15 with the end surfaces of the recesses, which serve as stop shoulders. In like manner the engagement of the rollers within the guides 40 formed by the recesses, prevents the endwise movement of the rollers relative to the leaves.

The insertion of the rollers between the end portions of the leaves acts to separate 45 the same throughout said portions, and therefore I prefer to separate the central portions of the leaves by the insertion of spacing members or plates 18, between central portions thereof adjacent to straps 11, 11.

50 In Figs. 4, 5 and 6 of the drawings, I have shown a modified construction of my invention wherein I provide a plurality of rollers 20, but in this instance each roller has a single flange 21, identical in form 55 with those hereinbefore described, but located at the central portion of the roller. This flange engages an elongated slot or guideway 22, formed at the central portion of the leaf. This form of roller and guide 60 is otherwise identical in its location and function with the before described form of my device. In order to prevent the rollers from being disposed from their positions and the flanges disengaged from their guide

slots in the instance of a severe shock to 65 the spring, which would result in an excessive spreading of the spring leaves, I choose to provide a pin 23 which extends through the lower portion of the flange of each roller, as shown in Figs. 4 and 7. The pin is 70 secured in an aperture formed in that portion of the flange which projects below the lower surface of the spring leaf, and is adapted to extend in either direction beyond the side margins of the slot. The 75 pin thus acts to prevent the flange from being removed from the slot and furthermore acts to retain the flange in position so that the flanges are maintained at all times upon the under surface of said rollers. 80

The flanges are formed to extend throughout one-half of the circumference of the roller for the purpose of providing means for retaining and for guiding the movement of the rollers between the leaves, and at the 85 same time allowing the rollers to coact throughout the entire width of the spring leaf immediately above the roller. So also it is unnecessary to remove any portion of the metal of the uppermost spring leaf, 90 thereby materially weakening the same, at that point where the maximum bending moment occurs. The provision of the inclined end surfaces 16 of the flanges is now 95 apparent, namely, to permit a greater rotative movement of the roller without danger of the ends of the flange striking the upper spring leaf, thereby interfering with the free movement of the members.

The principal advantage of my invention 100 is the simplicity of construction of the rollers, the absence of cages and bearings for the rollers which require frequent attention and repair, and the low cost of manufacture and maintenance. A further feature of my 105 invention is that an ordinary spring may be easily provided with anti-friction rollers of this form with very little expense and labor. The rollers are easily accessible for cleaning and oiling and may be easily replaced 110 should one become broken or displaced.

The details of construction of my invention may be variously modified without departing from the spirit of my invention, and for that reason I do not wish to be limited 115 to the particular form herein shown and described, except in so far as pointed out in the appended claims.

I claim as my invention:

1. A spring, comprising a plurality of 120 superimposed flexible plates, a roller interposed between two of said plates and provided with a radially extending projection, one of said plates being provided with a recess adapted to be engaged by said projection. 125

2. A spring comprising a plurality of 130 superimposed flexible plates, a roller inter-

posed between the plates and provided with a radial projection, one of said plates being provided with stop shoulders, between which said projection is adapted to extend.

5 3. A spring, comprising a plurality of superimposed flexible plates, a plurality of rollers interposed between said plates, each of said rollers being provided with a radially extending projection, and one of said 10 plates in contact with each of said rollers being provided with a recess adapted to be engaged by said projection.

4. A spring, comprising a plurality of superimposed flexible plates, a plurality of 15 transversely extending rollers interposed between said plates, each of said rollers being provided with a radially extending projection, and one of said plates in contact with each of said rollers being provided with a 20 longitudinally extending recess adapted to be engaged by said projection.

5. A spring, comprising a plurality of superimposed flexible plates, a plurality of rollers interposed between said plates, each 25 of said rollers being provided with a flange extending radially from the rollers, substantially throughout one-half of the circumference of said roller, and one of the 30 plates in contact with each roller being provided with a longitudinal recess adapted to be engaged by said flange.

6. A spring, comprising a plurality of superimposed flexible plates, a plurality of rollers mounted between said plates, and extending transversely thereof, each of said 35 rollers being provided at its ends with correspondingly arranged and outwardly extending flanges surrounding substantially one-half the circumference of the roller, and 40 one of the plates in contact with said rollers being provided at its margins with longitudinally extending recesses, adapted to be constantly engaged by the flanges of each of said rollers.

45 7. A spring, comprising a plurality of superimposed flexible plates, each of said plates extending beyond the extremity of the plate immediately below, a plurality of rollers mounted transversely between said 50 plates, each of said rollers being provided with an outwardly extending flange surrounding substantially one-half of the circumference of the roller, the plate in contact with the lower surface of each of the 55 rollers being provided with a longitudinally extending recess formed in the end portions of the plate and beyond the ends of the plate immediately below, said recess be-

ing adapted to be constantly engaged by the flange of each of said rollers.

8. A spring, comprising a plurality of superimposed flexible plates, each plate extending beyond the ends of the plate immediately below, a plurality of transversely extending rollers mounted between said 60 plates, each roller being provided at its ends with outwardly extending flanges surrounding substantially one-half the diameter of the roller, the plate in contact with the lower surface of each of said rollers being 65 provided with longitudinally extending recesses adapted to be constantly engaged by the flanges of each roller, said recesses being located in the end portions of the plate and beyond the ends of the plate immediately below.

9. A spring, comprising a plurality of superimposed flexible plates, a plurality of rollers mounted between said plates, and extending transversely thereof, each of said 70 rollers being provided with an outwardly extending flange surrounding substantially one-half the circumference of the roller, and one of the plates in contact with said rollers being provided with a longitudinally extending recess, adapted to be engaged by the flange of each roller, and means for retaining said flange in engagement with said recess.

10. A spring, comprising a plurality of superimposed flexible plates, each of said plates extending beyond the extremity of the plate immediately below, a plurality of rollers mounted transversely between said 75 plates, each of said rollers being provided with an outwardly extending flange surrounding substantially one-half of the circumference of the roller, and adapted to extend beyond one of the plates in contact with the roller, said plate being provided 80 with a longitudinally extending recess located in the end portions thereof and beyond the ends of the plate immediately below, said recess being adapted to be constantly engaged by said flange, and a pin extending 85 through the portion of the flange beyond said plate.

In testimony that I claim the foregoing as my invention I affix my signature in the presence of two witnesses, this 4th day of April A. D. 1914.

HERMAN A. POPPENHUSEN.
